ATTORNEY

UNITED STATES PATENT OFFICE.

CHARLES H. HARRIS, OF CRANSTON, RHODE ISLAND, ASSIGNOR OF ONE-FOURTH TO DAVID E. WOOD, OF COLLEGE POINT, NEW YORK, AND ONE-FOURTH TO ALFRED E. WOOD, OF BROOKLYN, NEW YORK.

ARTIFICIAL SHINGLE.

Application filed June 7, 1923. Serial No. 643,902.

To all whom it may concern:

Be it known that I, CHARLES H. HARRIS, a citizen of the United States, residing at Cranston, in the county of Providence and 5 State of Rhode Island, have invented certain new and useful Improvements in Artificial Shingles, of which the following is a specification.

The objects of my invention are,—first, 10 to provide a means to secure or lock the lowermost edge of the shingle to the roof to prevent it curling up or warping, and second, to provide a starting strip which will act as a gauge along the eaves and enable 15 the workman to apply the shingles accurately and rapidly.

These objects are attained by my shingle and starting strip illustrated in the accompanying drawings in which Fig. 1 is a plan 20 view of a portion of a roof upon which the said invention has been applied; Fig. 2 is an enlarged rear or bottom view of one of my shingles; Fig. 3 is an enlarged rear or bottom view of the starting strip; Fig. 4 is 25 a still larger plan view of a portion of a roof upon which some of the shingles have been applied, and Fig. 5 is a sectional detail on the line 5—5 of Fig. 3.

Like reference characters refer to like 30 parts in the several figures.

Referring now to the drawings, the shingle, 10, is made, preferably square, of any desirable material, and of a size to provide convenience in manufacturing and application as well as a neat appearance when applied to the roof. Each corner of the shingle has a nail hole, 11, equidistant from the sides while one corner, 12, as for example the lowermost corner, is folded back 35 flat against the under side, forming a close crease 13, which is perpendicular to the vertical diagonal of the square.

The starting strip, 14, is of the same thickness as the shingle, is made of the same 40 material, and is in length preferably a trifle less than twice the diagonal length of the square shingle, 10. A portion, 15, is folded back forming a crease 16, and a hole, 17, passes through the two thicknesses of the starting strip, 14, midway of the length and the same distance from the crease, 16, as the hole, 11, in the corner, 12, of the shingle, 10, is from the crease 13.

In applying the shingles the starting

strips are attached in the following manner: The corner, 12, of one of the shingles 10, is opened out and a flat headed nail, 11', of the type commonly used for attaching artificial shingles is driven through the hole, 11, and the hole, 17, in the starting strip, 14, into the roof, 18, so that the crease, 16, of the starting strip comes flush with the eaves or lowermost edge of the roof. The shingle is then pushed or dropped back flat against the roof, covering the nail in 60 the corner, 12, and nails, 11', are then driven through the other three holes, 11, securing the starting strip as well as the shingle to the roof. Then another starting strip is attached in the same way leaving a clearance 65 between the abutting ends of the two starting strips equal to the diameter of a nail and so on all along the eaves. Then a shingle is attached at the juncture of every two starting strips, the nail through its 70 corner, 12, being driven between the strips as shown in the drawings.

It is customary in order to give the roof a solid appearance to have a double thickness of shingles at the eaves and this is accomplished by the fold in the starting strip 75 as above described.

It will be noted that the first row of shingles may be easily alined by causing the corners to meet as shown in Fig. 4.

The second row of shingles is then easily attached and alined by fitting the folded corner, 12, of each shingle into the angle formed by two shingles of the first row as 80 shown in Fig. 4. The body or upper part of the shingle lies flat, the corner, 12, occupying the recess formed by the corners of the two lower shingles. All the nails and nail holes are covered, and because the lower edge of each shingle lies flat against the parts beneath it there can be no openings or 85 crevasses left through which rain, wind, or snow can creep.

It will be noted that irrespective of the form of the upper half of a shingle, its lower half preferably takes the form of a right isosceles triangle whose angular corner is folded under and flatly creased horizontally and parallel to the diagonal passing through the side corners of the shingle, whereby said folded under corner fits flatly and precisely 100 into the right angular space formed by or between the adjacent side corners of the two

shingles over which the shingle having the folded under corners is placed, as clearly shown in Fig. 4 in one portion of which is indicated how the fastening nail is driven 5 through the folded under corner, 12, while the main portion of such shingle is brought temporarily forward or upward from its flat position.

I claim:

- 10 1. In shingle roofing, a plurality of like shingles of substantially rectangular form having predetermined holes in the four corner portions thereof, said holes being spaced uniformly from the edges of said shingles; 15 one corner of each of said shingles being folded under forming a flat crease parallel to a diagonal of the shingle and equidistant therefrom in the several shingles, a fastener adapted to pass through the hole of said 20 folded under portion so that the head thereof will be covered by the main portion of the shingle, and a series of starting strips of uniform dimensions spaced from each other to allow the passage therebetween of 25 one of said fasteners, each strip having a predetermined hole formed therethrough of uniform location with respect to the ends and bottom edge thereof for co-operation with the corresponding hole in the folded 30 under corner of a shingle.
2. In shingle roofing, a plurality of like shingles the lower portion of each of which is of right isosceles triangular form and having its corner folded under and creased 35 along a horizontal line perpendicular to the vertical diagonal constituting a bisector of the right angular corner, said folded under corner having a hole formed therethrough, and a series of starting strips, each of a 40 length substantially equal to a multiple of

the horizontal diagonal of the shingles and of a width greater than the aforesaid triangular portion of a shingle, the lower edge portion of the starting strip being straight and unbroken and provided with a hole in 45 its center as far from its lower edge as the hole aforesaid in the folded under corner is spaced from the crease.

3. In shingle roofing, a plurality of shingles each having an isosceles triangular lower portion, the lower point of which is folded back and under the main portion around a folding line horizontal and parallel to the diagonal passing through the side corners of the shingle, 50 said folded under point having a hole formed therethrough at a predetermined distance from the folding line, said folded under point being shaped to fit directly into the angular space between the 55 abutting side corners of the two shingles covered by the shingle having the folded under point, and a series of starting strips for application adjacent to the eaves, each strip having a hole formed therethrough 60 and spaced from its lower edge substantially the same distance as said shingle point hole is spaced from the folding line in the shingle, said hole in the starting strip being spaced from one end of the starting strip 65 a distance substantially equal to the diagonal length of the shingle between its side corners, and a fastener adapted to pass through the folded under point of a shingle and said starting strip hole and be covered 70 and hidden by the main portion of the shingle.

In testimony whereof I affix my signature.

CHARLES H. HARRIS.
